UNITED STATES PATENT OFFICE.

MAX W. BECTON, OF NEW YORK, N. Y.

DESIGN FOR A DISPLAY-BOX.

SPECIFICATION forming part of Design No. 30,427, dated March 28, 1899.

Application filed March 2, 1899. Serial No. 707,533. Term of patent 7 years.

To all whom it may concern:

Be it known that I, MAX W. BECTON, a citizen of the United States, residing at the city of New York, borough of Manhattan, in the county and State of New York, have invented and produced a new and original Design for a Display-Box, of which the following is a specification, reference being had to the accompanying drawing, forming a part thereof, in which is represented a perspective view of a display-box embodying the features of my design.

The body A of the box is flat at the bottom and tapers at the top from the back downwardly to the front, and at the upper front surface of the body of the box a horizontal panel B is formed, and a series of depressions C appear in the top of the box-body, extending from the panel B to the rear. These depressions simulate cells parallel with each

other and with the sides of the box. A cover D apparently rises from the back of the box, and the cover extends rearward at an acute angle to the box-body, the two parts being apparently integral. The cover consists of a top or main panel d, an upper panel d', and side panels d², the side panels appearing to extend beyond the plane of the sides of the body A of the box, and the side panels d² of the cover are inclined at their free longitudinal edges, being narrowest where they connect with the top panel d'.

I claim—

The design for a display-box herein shown and described.

MAX W. BECTON.
